UNITED STATES PATENT OFFICE.

HARRY SEBELL, OF BOSTON, MASSACHUSETTS, ASSIGNOR TO ARTHUR H. PARKER, OF LEXINGTON, MASSACHUSETTS.

SEALED CAN.

Application filed May 16, 1928. Serial No. 273,098.

This invention relates to a tin can and particularly to a can in which the sealing of the can is accomplished through the medium of a U-shaped sealing strip which embraces 5 sealing flanges formed on the can body and the cover respectively.

One of the principal objects of the invention is to provide an improved can of this type which is constructed so as to facilitate 10 the removal of the sealing strip preliminary to opening the can. This is accomplished by means of a can-opening strip which is incorporated in the can when the latter is sealed in such a way that the can-opening 15 strip is interlocked with the sealing strip adjacent one end of the latter so that the application of force to the can-opening strip will loosen the sealing strip sufficiently so that the latter may be readily removed from 20 the can. After the sealing strip has been removed the cover may be pried off the can in any suitable way.

In order to give an understanding of the invention, I have illustrated in the drawings 25 a selected embodiment thereof which will now be described after which the novel features will be pointed out in the appended claims.

In the drawings:

30 Fig. 1 is a partial sectional view of a can embodying my invention and showing the manner in which the can is unsealed.

Fig. 2 is a plan view of Fig. 1 with a part broken out.

35 As stated above my invention relates to that type of can which is sealed through the medium of a U-shaped sealing strip that embraces sealing flanges formed on the can body and can cover respectively. In the 40 drawings 1 indicates the can body which has at its open end a laterally-extending sealing flange 2. The cover or closure is shown at 3, it being of a size to fit into the open end of the can and being provided with the sealing flange 4 that overlies the sealing flange 2 of the can body. 5 indicates the usual gasket which is commonly used between the sealing flanges of the can body and cover. The U-shaped sealing strip is shown at 6 and this embraces the two sealing flanges 2 and 4 as usual in cans of this type.

In the illustrated embodiment of the invention the can cover is also formed with a clamping flange 7 (herein shown as a two-ply flange) which overlies the upper leg 8

of the sealing strip, said clamping flange 7, sealing strip 6 and sealing flanges 2 and 4 being firmly pressed together to make a tight closure.

A can having this construction is illustrated in my co-pending application Serial No. 252,863, filed February 8th, 1928, and a can having the same general features of construction is illustrated in my Patent No. 1,647,056, dated October 25th, 1927, the difference between the can herein illustrated and that shown in my patent being that in the can herein illustrated the clamping flange 7 is a two-ply flange and the sealing flange 4 of the cover is a one-ply flange 60 while in the patent the clamping flange is a 65 one-ply flange and the sealing flange of the cover is a two-ply flange.

In sealing a can of this type the sealing strip 6 extends around the can with the two 70 ends 9 thereof meeting or overlapping and in order to open this can it is necessary first to remove the sealing strip after which the can cover can be pried out of the can. The 75 operation of removing the sealing strip involves first that of pulling one end 9 of the sealing strip loose after which said strip may be readily pulled off from the can.

My present invention relates to a novel 80 means incorporated in the can for thus loosening one end of the sealing strip thereby 85 facilitating the opening of the can. This is accomplished by employing a can-opening strip which is interlocked with the sealing strip near one end 9 thereof and is so arranged that a pull on the can-opening strip 90 will draw one end 9 of the sealing strip loose from the can. The can-opening strip is indicated at 10 and it is preferably made of a thin flexible metal. This can-opening 95 strip normally lies against the top of the can closure 3 and, as stated above, it is interlocked with the sealing strip near one end.

This is herein accomplished by carrying the can-opening strip around the clamping 100 flange 7 and between the latter and the leg 8 of the sealing strip and then around the said leg 8 of the sealing strip and between the latter and the sealing flange 4 of the cover.

If desired, the can-opening strip may extend clear across the cover and may be thus interlocked with the sealing strip at both ends as shown in the drawings, although this is not essential. It is, however, desirable, 110

that said can-opening strip should be interlocked with the sealing strip adjacent one end of the latter. This can-opening strip may be readily incorporated in the can during the can-sealing operation and when in place it lies flatly against the can closure and makes no appreciable projection since the strip 10 is a very thin strip.

To open the can which embodies this invention it is simply necessary to grasp the can-opening strip and pull outwardly thereon. This outward pull will serve to force one end 9 of the sealing strip out from its sealing engagement with the sealing flanges 2 and 4 as shown in dotted lines Fig. 1, thus placing said end of the sealing strip in position where it can be readily grasped by the fingers or by pliers or other instruments and thus entirely removed from the can.

The difficult part of opening a can which is closed with a U-shaped sealing strip, such as 6, is that of loosening one end of the sealing strip. After an end of the sealing strip is loosened the latter can be readily pulled away from the can. My invention provides means whereby an end of the sealing strip can be easily and instantly loosened thus facilitating the opening of the can.

If both ends of the can-opening strip are anchored or interlocked with the sealing strip then said can-opening strip may be used as a bail to carry the can as shown in dotted lines Fig. 1. Said strip 10 is of very flexible material and since it follows the contour of the can cover as shown in full lines Fig. 1, it is of sufficient length to function as a bail.

I claim.

1. A sealed can comprising a can body having a laterally-extending sealing flange, a can cover also having a laterally-extending sealing flange, a U-shaped sealing strip embracing said sealing flanges, and a can-opening strip separate from the sealing strip and interlocked with the latter near one end thereof, whereby a pull on the can-opening strip will loosen one end of the sealing strip.

2. A sealed can comprising a can body having a laterally-extending sealing flange, a can cover also having a laterally-extending sealing flange, a U-shaped sealing strip embracing said sealing flanges, and a can-opening strip separate from the sealing strip and lying on the outer face of the cover and having one end interlocked with the sealing strip adjacent an end of the latter.

3. A sealed can comprising a can body having a laterally-extending sealing flange, a can cover also having a laterally-extending sealing flange, a U-shaped sealing strip embracing said flanges and a can-opening strip separate from the sealing strip and having

one end confined between the sealing strip and the sealing flange of the cover at a point adjacent an end of the sealing strip, whereby a pull on the can-opening strip will loosen said end of the sealing strip.

4. In a sealed can, a can body having a laterally-extending sealing flange, a can cover also having a laterally-extending sealing flange, a U-shaped sealing strip embracing said flanges, said cover having a clamping flange overlying the sealing strip, and a can-opening strip encircling the clamping flange and confined between the sealing strip and the sealing flange of the cover at a point adjacent one end of said sealing strip.

5. In a sealed can, a can body having a laterally-extending sealing flange, a can cover also having a laterally-extending sealing flange, a U-shaped sealing strip embracing said flanges, said cover having a clamping flange overlying the sealing strip and a can-opening strip extending across the cover and having each end thereof clamped between the sealing strip and the sealing flange of the cover.

6. A sealed can comprising a can body having a laterally-extending sealing flange, a can cover also having a laterally-extending sealing flange, a U-shaped sealing strip embracing said flanges, and a can-opening strip extending across the cover and having each end thereof clamped between the sealing strip and the sealing flange of the cover.

7. A sealed can comprising a can body having a laterally-extending sealing flange, a cover also having a laterally-extending sealing flange, a U-shaped sealing strip embracing said sealing flanges, said cover having a clamping flange overlying the sealing strip, and a can-opening strip extending diametrically across the cover and each end thereof passing around the clamping flange and being clamped between the sealing strip and the sealing flange of the cover.

8. A sealed can comprising a can body having a laterally-extending sealing flange, a cover also having a laterally-extending sealing flange, a U-shaped sealing strip embracing said sealing flanges, said cover having a clamping flange overlying the sealing strip, and a can-opening strip extending diametrically across the cover and each end thereof passing around the clamping flange and being clamped between the sealing strip and the sealing flange of the cover, one of the points where said can-opening strip is so clamped being adjacent one end of the sealing strip.

In testimony whereof, I have signed my name to this specification.

HARRY SEBELL.
